UNITED STATES PATENT OFFICE.

WILLIAM H. LANE AND JOHN P. LEDGER, OF LEOMINSTER, MASSACHUSETTS.

DESIGN FOR A BARRETTE.

42,086.

Specification for Design.

Patented Jan. 9, 1912.

Application filed November 30, 1910. Serial No. 595,005. Term of patent 3½ years.

To all whom it may concern:

Be it known that we, WILLIAM H. LANE and JOHN P. LEDGER, citizens of the United States, residing at Leominster, in the county of Worcester and State of Massachusetts, have invented a new and original and ornamental Design for Barrettes, of which the following is a specification, reference being had to the accompanying drawing, forming a part thereof.

In the drawings, Figure 1 is a back view

of the barrette; and Fig. 2 is a longitudinal side view of the same.

We claim:—

The ornamental design for a barrette, as shown.

WILLIAM H. LANE.
JOHN P. LEDGER.

Witnesses:

M. F. CRANE,
JAMES CONNAUGHTON.
